Des. 228,092
Patented Aug. 7, 1973

228,092

ASPHALT MILL

Sylvan G. Stepp, North Branch, Minn. 55056

Filed Dec. 17, 1971, Ser. No. 209,506

Term of patent 14 years

Int. Cl. D15—99

U.S. Cl. D55—1 R

FIG. 1

FIG. 4

FIG. 2

FIG. 5

FIG. 3

FIG. 1 is a front side elevational view of an asphalt mill embodying my design;

FIG. 2 is a rear side elevational view of the same;

FIG. 3 is a top plan view of the same;

FIG. 4 is an end elevational view of the same; and

FIG. 5 is an opposite end elevational view of the same.

I claim:

The ornamental design for an asphalt mill, as shown and described.
